UNITED STATES PATENT OFFICE.

PETER CHRISTMAN, OF GREEN BAY, WISCONSIN.

ROTARY PUMP.

1,092,139.

Specification of Letters Patent. Patented Apr. 7, 1914.

Application filed May 8, 1913. Serial No. 766,370.

To all whom it may concern:

Be it known that I, PETER CHRISTMAN, a citizen of the United States, residing at Green Bay, in the county of Brown and State of Wisconsin, have invented certain new and useful Improvements in Rotary Pumps; and I do declare the following to be a full, clear, and exact description of the invention, such as will enable others skilled in the art to which it appertains to make and use the same.

This invention relates to pumps, and more especially to those which rotate, and the object of the same is to produce a pump of this character having a non-rotary circular or cylindrical cylinder which may be submerged, and a rotary eccentrically mounted piston having two wings which are revolved within the cylinder to force the water upward. This object is carried out by constructing the pump in detail in the manner hereinafter more fully described and claimed, and as shown in the drawings wherein—

Figure 1 is a side elevation of the lower portion of this pump, and a sectional view through the lower end of the outlet pipe. Figs. 2 and 3 are enlarged cross sections on the line 2—2 of Fig. 1, showing the internal parts in different positions. Fig. 4 is a vertical sectional view of the pump. Fig. 5 is an enlarged bottom plan view of the cap. Fig. 6 is an enlarged plan view of the plug.

The cylinder 1 of this pump stands upright, is provided along one side with a series of inlet ports 2, and has its lower end closed by a plug 3 whose upper face contains a central socket 4 and an eccentric groove 5. The upper end of the cylinder is closed by a cap 6 which is preferably screwed onto the cylinder as shown, and through this cap is an eccentric opening surrounded by a nipple 7 to which the suspension pipe 8 is screwed. I may here say that this pipe carries the entire pump and by it the cylinder is depressed to a suitable point below the water level, so that cool water may be taken in through the ports 2 and passed up the pipe 8 to a suitable nozzle or other point of use not necessary to show.

The piston 11 is cylindrical and of a proper size to sit at its lower end into the groove 5, when one side of the piston rests against the inner face of the cylinder at a point 12 just in advance of the row of ports 2; and the upper end of the piston is

journaled in the eccentric hole through the cap, and preferably within a packing 13 carried therein as shown.

The numeral 14 designates a coupling member whose lower end is screwed into the upper end of the piston and whose upper end extends through the cap and is pierced with lateral outlet ports 15; and the upper end of the coupling is closed, and from it rises a shaft 17 to which rotary motion is imparted by any suitable means not necessary to illustrate. The walls of the piston at diametrically opposite points are provided with upright slots 18 and 19 whose edges are rounded as shown.

Seated in the socket 4 is a pin 20 which rises along the true axis of the cylinder 1 but is disposed eccentrically within the piston 11 as shown, and hinged at 21 on this rod or pin is a pair of abutments 22 and 23, each having its forward side dished or cut away as at 24, its outer edge rounded so as to fit within the cylinder, and its side faces adjacent said rounded edge packed as 25 at 25. The length or height of these abutments is the same as the length of the slots 18 and 19, their thickness corresponds to the width of said slots but their packed edges 25 will fit the slots closely, and their radial dimensions are such that they extend from the pin or rod 20 outward to water-tight contact with the interior of the cylinder 1.

The parts constructed as above described are assembled as shown in the drawings, and the lower end of the suspension pipe 8 carrying this pump is let down into the water to a suitable point, and rotary power applied to the shaft 17. When now the piston revolves in the direction of the arrow until its slots 18 and 19 are directly in alignment with the center of the pin or rod 20, the abutments or wings 22 and 23 stand in direct alignment with each other and opposite the point 12, and adjacent this point the packed edge 25 of the wing 23 will close the slot 19 water-tight whereas the opposite wing 22 projects for a considerable distance through the other slot 18 as shown. If now the piston continues to rotate in the direction of the arrow, all the water therein forward of said wing 22 must pass through its dished face 24, the slot 18, and into the interior of the piston, whence it passes upward through the coupling and out its ports 15, and thence on upward through the suspension pipe 8. Meanwhile the other abut-

ment has moved from the point 12 past the inlet ports 2, and the space behind it is growing constantly larger so that it admits a fresh charge of water behind it, while the 5 charge of water ahead of it is subjected to the action just described.

Attention is invited to the fact that, owing to the peculiar disposition of parts, when the abutments stand diametrically opposite each 10 other the one whose outer edge stands at the point 12 is moving quite slowly and the opposite abutment quite rapidly. The result is that the last-named abutment will rapidly eject the charge of water ahead of it, and as 15 it is doing so draws farther and farther inward in the slot in the piston through which it projects, until finally its packed edge 25 closes said slot to the passage of any further water. Meanwhile the other abutment which 20 started at the point 12 moves rather slowly until it passes the inlet ports 2, and from there on it moves with increasing velocity to a point opposite the point 12, so that a fresh 25 charge of water is sucked in through the inlet port because the back of this abutment is closed to the outlet through its own slot, while the water forward of it during this motion is forced to pass through its dished 30 face and slot and upward through the outlet.

30 A rotary pump constructed as described may be made of the desired materials and to the proper proportions, and it needs no lubrication because the parts which move over each other are constantly submerged 35 and always wet. A little experience will develop the proper speed of rotation which does the most effective work without "churning" the water or unduly agitating it near the bottom of a stream or well.

40 What is claimed as new is:

1. In a rotary pump, the combination with an upright cylinder pierced with a row of inlet ports along one side, a plug closing its lower end, a cap closing its upper end and 45 having an off-center nipple, and an outlet pipe leading upward from the nipple; of a concentric pin upstanding from the plug at the center of the cylinder, an eccentric rotary piston inclosing said pin and contacting with 50 the wall of the cylinder just in advance of said row of ports, the piston having an upright slot through its wall, means leading up the outlet pipe for rotating said piston, and a wing hinged on said pin and projecting 55 through said slot in contact with the wall of the cylinder and dished in its front face.

2. In a rotary pump, the combination with an upright cylinder provided with an inlet opening in one side, a plug closing its lower 60 end, a cap closing its upper end and having an off-center opening, and an outlet pipe leading upward therefrom; of a pin upstanding from the plug, an eccentric rotary

piston inclosing said pin and contacting with the wall of the cylinder just in advance of 65 said inlet, the piston having an upright slot through its wall, means for rotating said piston, and a wing hinged on said pin and projecting through said slot in contact with the wall of the cylinder, the front face of 70 said wing in the direction of rotation being dished and its front and rear faces at its outer edge being packed, for the purpose set forth.

3. In a rotary pump, the combination with 75 an upright cylinder pierced with a row of inlet ports along one side, a plug closing its lower end and provided with a central socket and an eccentric circular groove, a cap closing its upper end and having an eccentric 80 nipple, and an outlet leading upward from the nipple; of a pin seated in said socket, an eccentric rotary piston inclosing said pin and seated in said groove, its outer face contacting with the wall of the cylinder just in 85 advance of said row of ports, the piston having opposite upright slots through its wall, means leading out the outlet pipe for rotating said piston, and wings hinged on said pin and projecting through said slots in contact with 90 the wall of said cylinder, the front faces of said wings in the direction of their rotation being dished.

4. In a rotary pump, the combination with 95 an upright cylinder pierced with a row of inlet ports along one side, a plug closing its lower end and provided with a central socket and an eccentric circular groove, a cap closing its upper end and having an eccentric 100 nipple, and an outlet pipe leading upward from the nipple; of a pin seated in said socket, an eccentric rotary piston inclosing said pin and seated in said groove, its outer 105 face contacting with the wall of said cylinder just in advance of said row of ports, the piston having opposite upright slots through its wall, a coupling screwed into the upper 110 end of the piston and having lateral outlet ports communicating with said outlet pipe, a rod within the latter connected with said 115 coupling for rotating the piston, and wings hinged on the pin and projecting through said slots and having rounded outer edges making contact with the wall of the cylinder, the front face of each wing in the direction of rotation being dished and its front and rear faces along its outer edge being packed, for the purpose set forth.

In testimony whereof I have hereunto set my hand in presence of two subscribing witnesses.

PETER CHRISTMAN.
